[57] CLAIM

The ornamental design for a truck wind deflector, as
shown and described.

DESCRIPTION

FIG. 1 is a perspective view of a truck wind deflector
showing my new design;

FIG. 2 is a front elevation view thereof;

FIG. 3 is a top plan view thereof;

FIG. 4 is a side elevation view thereof; and

FIG. 5 is a rear elevation view thereof.

The broken lines in the drawing are for illustrative
purposes only.
